UNITED STATES PATENT OFFICE.

FRANCIS J. COLE, OF SCHENECTADY, NEW YORK.

LOCOMOTIVE DRIVING-BOX.

1,338,491.

Specification of Letters Patent. Patented Apr. 27, 1920.

Application filed September 15, 1919. Serial No. 323,779.

To all whom it may concern:

Be it known that I, FRANCIS J. COLE, of Schenectady, in the county of Schenectady and State of New York, have invented a 5 certain new and useful Improvement in Locomotive Driving-Boxes, of which improvement the following is a specification.

My invention relates to locomotive driving boxes of the class or type in which the bearing comprises a plurality of adjustable sections, an instance of which is exemplified in Letters Patent of the United States No. 1,218,375, granted and issued to me under date of March 6, 1917. The object of my 10 present invention is to provide a driving box of the type referred to, in which the bearings sections shall be mutually adjustable and free to assume their normal positions relatively to the box, and lost motion, 15 resultant upon wear of the box and of the bearings, may, as to both said members, be simultaneously taken up by the ordinary pedestal wedge.

The improvement claimed is hereinafter 20 fully set forth.

In the accompanying drawings: Figure 1 is a front view, in elevation, of a locomotive driving box illustrating an embodiment of my invention; Fig. 2, a plan or top 25 view of the same; Fig. 3, a longitudinal central section; Fig. 4, a transverse section, on the line *a a* of Fig. 3; Fig. 5, a plan view of the left hand section of the driving box; Fig. 6, a front view of the same; Fig. 7, a 30 plan view of the right hand section of the driving box; and, Fig. 8, a front view of the same.

Referring descriptively to the specific embodiment of my invention which is here- 40 in exemplified, it is, as in Letters Patent No. 1,218,375 aforesaid, illustrated, as applied in a locomotive driving box which is fitted, with the capacity of relative vertical movement, between a shoe, 1, and a 45 wedge, 2, which is operated by a screw, 2^a, in a locomotive frame pedestal, the jaws, 3, 3, of which, extend from an upper frame rail, 4, to a lower frame rail, 5. The portion of the weight of the locomotive which 50 is supported by the journal, 6, of the driving axle on which the driving box rests, is applied to the top of the driving box through a spring saddle, 7, which fits over the upper frame rail, and supports a driv-

ing spring, which is not shown, in the usual 55 manner.

The driving box proper is made in two independent and relatively movable sections, each of which is of substantially inverted L form, comprising a top horizontal 60 member, 8, and a vertical side member, 8^a, integral therewith, and depending, at a right angle, therefrom. As most clearly shown in Fig. 7, the top member, 8, of what may, descriptively, be termed the right 65 hand section of the driving box, is shorter, in the line of the driving axle, than the top member of the other, or left hand section, and it overlaps, and rests on, the top of the last named member, fitting between end 70 flanges, 8^c, thereon. A recess, 8^e, (Figs. 4 and 6) is formed in the lower face of the top member of the left hand section of the box, and stops, 8^h, are formed on the inner sides of both the sections thereof, at and 75 adjoining their lower ends, the functions of which recess and stops will be presently described.

The journal bearing or "brass" of the driving box, is formed in three sections, and 80 comprises a top section, 12, which is fitted in the recess, 8^e, of the top member of the left hand section of the box, and two side sections, 12^a, 12^b, each of which extends both above and below the axial line of the 85 journal, and is fitted between the journal and the vertical side member of one of the sections of the driving box. Undue downward movement of the side sections of the journal bearings is prevented by the side 90 stops, 8^h, on the vertical members of the driving box sections, and the bearing sections are prevented from sliding out of position endwise, by a hub thrust plate, 16, and a retaining plate, 17, formed on, or fixed to, 95 the ends of the left hand driving box section. By reference to Fig. 4, it will be seen that the journal bearing sections are disposed symmetrically about the axial line 100 of the journal, and that they as well as the overlapping sections of the driving box, are relatively adjustable, the journal box sections both horizontally and vertically, and the driving box sections, horizontally.

Proportionately as the top bearing section, 12, wears and becomes thinner, the right and left hand sections, 8, 8^a, 8, 8^b, of the driving box, slide down on the side bear-

ing sections, 12^a, 12^a, allowing them to preserve the correct axial relations to the driving axle, and as the side bearing sections wear thinner, the overlapping driving box sections, 8, 8^a, 8, 8^a, can be closed in nearer together by adjustment of the pedestal wedge, 2, as stated in the next succeeding paragraph.

When, by reason of knocking, pounding, or slackness of the bearing on the journal, it becomes necessary or desirable to take up wear or lost motion, the sections of the driving box, and the interposed journal bearing sections, may be manually closed together, by proper adjustment of the pedestal wedge, 2, by its operating screw, 2^a. The same function may, if preferred, be automatically performed by the application of one of the forms of automatic spring adjusted wedges which are well known and used in railroad practice, for automatically taking up slack in driving boxes of the ordinary construction.

The provision of overlapping top members in the driving box sections, sliding in a horizontal plane immediately above the axis of the bearing, enables the sections of the driving box to be held together, and at the same time allows adjustment for wear to be taken up by the pedestal wedge, no other adjustment or shimming being necessary, within the capacity of the wedge. Each of the bearing sections is free to move in the driving box, and its wear will be taken up in relation to the common axial line of the sections. It is well known, in practice, that when the ordinary driving box, with semi-circular bearing, becomes hot, it tends to grip the journal, and no means are available to relieve such gripping. In the operation of my invention, the release of the pedestal wedge simultaneously slacks up the driving box in the pedestal fit and the bearing sections around the journal. The only resistance experienced is that of the sliding of the top sections of the driving box, one on the other, but when the abutting surfaces are properly lubricated, the co-efficient of the friction will be very low.

I claim as my invention and desire to secure by Letters Patent:

1. The combination, in a locomotive engine, of a frame pedestal; a driving box located therein, and made in two independent sections, comprising members, one of which overlaps the other and rests thereon, with the capacity of relative horizontal movement; three journal bearing sections, disposed in the top and sides, respectively, of the driving box; means for effecting adjustment of the bearing sections, relatively to a common axial line; and means for applying weight to the top bearing section.

2. The combination, in a locomotive engine, of a frame pedestal; a driving box lo-

cated therein, and made in two independent sections, comprising members, one of which overlaps the other and rests thereon, with the capacity of relative horizontal movement; three journal bearing sections, disposed in the top and sides, respectively, of the driving box; means for effecting adjustment of the bearing sections, relatively to a common axial line; and a spring saddle, bearing on the top overlapping member of the driving box.

3. The combination, in a locomotive engine, of a frame pedestal; a driving box located therein, and made in two independent sections, comprising members, one of which overlaps the other and rests thereon, with the capacity of relative horizontal movement; three journal bearing sections, disposed in the top and sides, respectively, of the driving box, the backs of the side bearing sections being parallel, to afford capacity of vertical adjustment of said sections in the driving box; means for effecting adjustment of the bearing sections, relatively to a common axial line; and means for applying weight to the top bearing section.

4. The combination, in a locomotive engine, of a frame pedestal; a driving box located therein, and made in two independent sections, comprising members, one of which overlaps the other and rests thereon with the capacity of relative horizontal movement; three journal bearing sections, disposed in the top and sides, respectively, of the driving box; means for imparting relative horizontal movement to the sections of the driving box, to effect adjustment of the bearing sections, relatively to a common axial line; and means for applying weight to the top bearing section.

5. The combination, in a locomotive engine, of a frame pedestal; a driving box located therein, and made in two independent sections, comprising members, one of which overlaps the other and rests thereon, with the capacity of relative horizontal movement; a wedge interposed between one of the driving box sections and the adjoining jaw of the pedestal; means for imparting vertical movement to said wedge, to effect adjustment of the driving box sections, and of the bearing sections, relatively to a common axial line; and means for applying weight to the top bearing section.

6. A locomotive engine driving box, made in two independent and relatively adjustable sections, each of substantially inverted L form, comprising a horizontal top member and a vertical side member depending therefrom, the top member of one section overlapping and resting on the top member of the other section, and movable in a horizontal plane relatively thereto.

7. A locomotive engine driving box, made in two independent and relatively adjustable

sections, each of substantially inverted L form, comprising a horizontal top member and a vertical side member depending therefrom, the top member of one section over-
5 lapping and resting on the top member of the other section, and movable in a horizontal plane thereon, said last specified top member having end guides between which

the first specified top member is fitted, and a lower recess to receive a journal bearing sec- 10
tion.
